NONCONDENSABLE GAS PURGER

Louis P. Reiss, Marshall, Tex.

Application November 28, 1940, Serial No. 367,557

5 Claims. (Cl. 62—115)

This invention relates to commercial refrigeration and it has particular reference to a method and apparatus designed to purge a refrigerating system of objectionable non-condensable gases.

One object of the invention is to provide apparatus of an extremely simple and easily operated construction which is adaptable to that type of system in which a liquid refrigerant is employed and is extremely effective in purging the system of accumulated non-condensable gases entrained with the refrigerating fluid.

Still another object of the invention is to provide an apparatus and method for the purpose specified in which the refrigerating system may be purged of objectionable gases without interfering with the normal operation of the plant.

A further object of the invention is to provide a gas purger for use in a refrigerating system which purging unit does not require a reduction of the amount of refrigerating fluid used in normal operation to accomplish its results.

Still another object of the invention is to provide a purging device that subjects a thin layer of fluid refrigerant and non-condensable gases to a low temperature, effected by passing the fluid through a refrigerated zone containing water which is held at a temperature substantially that of ice or slightly above.

The invention has for another and important object, the provision of a purging system which may employ ice as its own refrigerating medium, produced either commercially or by direct expansion, the latter being desirable where commercial ice is difficult or expensive to obtain and in the use of automatic cooling, automatic valve means is provided to maintain uniform temperature of the refrigerating medium or zone.

A construction designed to carry out the invention will be hereinafter described together with other features of the invention.

The invention will be more readily understood from a reading of the following specification and by reference to the accompanying drawings, in which an example of the invention is shown, and wherein:

Figure 1 shows a purging system constructed in accordance with the present invention, employing commercial ice as the cooling medium, and

Figure 2 is a modified form of the invention wherein ice is produced in the fluid around the separator through the medium of direct expansion, which serves to maintain low temperature of the liquid in the zone through which the refrigerant is passed.

Since refrigerating systems employing carbon

dioxide, ammonia and like fluids as the refrigerating medium are well known to the art, it is not considered necessary to describe such a system. It is, however, important to mention that in the operation of any such refrigerating system, the results obtained or the temperature maintained, depends entirely on the suction pressure maintained. When any type of purger is put into operation requiring a refrigerant to obtain the desired temperature, the amount of such refrigerant will necessarily have to be reduced in order to maintain the suction pressure for the desired temperature. The travel of the refrigerant in an ordinary type of purger after it passes through the expansion valve until it enters the suction line to the compressor is generally very short. If no means of heat exchange between the refrigerant used and the gases to be cooled is provided other than the metal contact, much of the refrigerant will pass over to the compressor unevaporated. The unevaporated refrigerant passes to the compressor and reduces the capacity of the compressor, quite often forming frost on the cylinder walls as it will evaporate after it has entered the cylinder. By placing the refrigerating coil in a fluid such as is provided, and previously mentioned, a more rapid heat exchange between the gases to be cooled and the refrigerant is set up. This is brought about by convection currents which are set up in the water surrounding the coils.

In the foregoing it has been mentioned that purgers in which direct expansion is employed and which have a short travel for the refrigerant, some of the refrigerant is carried over into the cylinders of the compressor frequently causing frost to form on the cylinder walls which results in undue mechanical wear and loss of power. That ammonia or other refrigerant which passes off with the suction gases and whose refrigerating effect is greatly reduced thereby is not only detrimental to the normal operation of the system, the efficiency of the machine and causing undue wear, but this surplus refrigeration is a complete loss.

The present invention, as previously stated, utilizes a tank in which a predetermined water level is maintained, said water being maintained at a constant temperature through the medium of crushed ice wherein the separation of the condensed ammonia gases and other undesirable non-condensable gases is accomplished. It is a well known fact that in the present art that the best time to purge non-condensable gases from a system is that time when there are no dis-

turbances in the system such as is caused by a compressor operating and the gas and refrigerant moving in the regular cycle. The present invention is so constructed as to allow a purging operation to be performed at such time as the balance of the plant is shut down but which may also be used if the plant is running.

In the drawings, the numeral 10 designates an elongated cylindrical tank or container and having a separator 11 extending axially therethrough. A constant water level L is maintained through the medium of an overflow pipe 12 which is connected onto a drain line 13 located in the extreme bottom of the tank and which drain is ordinarily closed by valve 14. A core 15 is disposed within the separator 11 and is provided with a wire 16 of suitable gage spirally wound therearound. The outer diameter of the core is slightly less than the inner diameter of the separator 11 while the wire 16 is of sufficient weight to close the space between the pipe and core.

The lower end of the separator 11 is connected to a receiving tank 17 by means of a pipe 18 having an angle cut-off valve 19 mounted therein intermediate said tank and said separator 11. Condensed refrigerating fluid enters the tank 17 through a pipe 20 from the condenser (not shown) and is normally passed on through the liquor line 21, not shown. Under ordinary operating conditions, the non-condensable gases entrained with the fluid likewise pass with the fluid to the receiver 17. An accumulation of non-condensable gases causes excessive head pressures which are detrimental to the operation of the system in two ways. First, by increasing the power used to operate the compressor and, second, in reducing the amount of refrigerant that could be handled by the compressor if the head pressure were lowered by means such as herein provided. However, since the non-condensable gases accumulated above the liquor level in the receiver 17, due to differential temperatures, they are immediately drawn off through the pipe 18 with some ammonia gases and transferred into the separator 11, it being understood that the valve 19 is opened to carry out this operation.

As the gases attempt upward travel around the spiraled core 15 through the cooled area, the ammonia gases are sufficiently cooled to transform these gases into liquid and allow the same in liquid form to travel spirally down the core through the line 16 and back to the receiver 17 to be further utilized in the system.

The non-condensable gases usually consist of air and gases which are found in the system and which may enter in a number of ways. The non-condensable gases and air are drawn off from the separator 11 through the medium of an exhaust pipe 22 preferably inclined, as shown, and communicates with a valve 23, connected to one end of a flexible exhaust means 24, the latter terminating adjacent the bottom of a small glass container 25 which is filled approximately to its top with water or other liquid suited to the purpose. The function of this container of liquid is to enable the operator to view the gases as they escape the exhaust member 24 and pass upwardly through the liquid within the container in the form of bubbles.

By manipulating the valve 23, the flow of escaping gases, as well as the speed of their exhaust may be regulated whereby the gases entering the lower end of the separator 11 will be constrained to pass upwardly through said sep-

arator at such a rate that the ammonia gases will have sufficient time to condense and thereby be conserved.

In operation: water is placed in the tank 10 up to a pre-determined level and then crushed ice A is deposited in the container to float on or near the surface of said water so that the lowest temperature will be near the top of the tank. As the ice melts, the liquid therefrom will be drawn off from the tank 10 through the overflow drain 12.

When the purger has cooled sufficiently, the valve 23 may be opened to allow 40 to 50 bubbles per minute to escape through the exhaust hose 24, considered to be sufficient to determine the condition of the system and to purge the same of foul gases. When no bubbles appear, it is assumed that all non-condensable gases and air have escaped, whereupon the valve 23 is closed and after sufficient time has elapsed to allow all liquid ammonia in the separator 11 to drain back into the receiver, the valve 19 may then be closed.

When it is desired to drain the tank 10 for repairs or to prevent freezing in cold weather, the valve 14 may be opened to completely drain the said tank and overflow pipe 12.

From the foregoing, it may be seen that a purging system of extreme simplicity of construction and operation may be had. This system may be easily connected to any ammonia system, and the only important requirement is to place the device at a higher level than the receiver so that the liquefied ammonia may return by gravity to the receiver. The overflow pipe 12 will keep the water at a pre-determined level at all times.

Further, due to the provision of the spirals about the core 15 disposed in the separator 11, a thin layer of ammonia and non-condensable gases are subjected to a low temperature which medium of commercial crushed ice.

Attention is directed to the fact that while the core 15 within the separator 11 has spirals formed thereon by means of a wire secured to the outer periphery of said core this spiral core could be formed in any number of ways.

Referring now to Figure 2, showing the slightly modified form of the invention, the same characters of reference will be employed for indicating parts therein identical to those of the earlier described form of the invention, and since the form and relationship of these parts are the same, a description thereof is considered unnecessary.

The one feature of this latter form of invention which differs from that just described, lies in the use of direct expansion as a refrigerating means for the liquid in tank 10 instead of cracked ice A. The refrigerating medium in this modification consists of a coil of pipe 25', surrounding the vertically disposed separator 11 and whose coils are spaced midway between the exterior walls of the separator 11 and the interior wall of tank 10 in order that sufficient space will be provided for the accumulation of ice on the coils to the greatest possible thickness before touching either the separator 11 or tank walls. This heavy formation of ice will store the greatest amount of refrigeration in a given sized tank and will also prevent distortion of either the separator 11 or the side walls of tank 10 in the event an operator should fail to inspect the unit or failure of the automatic valve, later identified, to function.

The pipe 26, serving the coil 25' is connected to the high side of the ammonia system while the pipe 27, opposite, extends to the suction side of the system.

It has been stated that uniformity of temperature of the liquid in the tank 10 is a desideratum for efficient operation of the purger. In this connection, it is pointed out that the thermostatically operated valve 28 is incorporated between pipe 26 and coil 25' in order that the temperature of the liquid in the tank 10 will be 38° or below. It is to be understood that use of this automatic valve 28 is optional since in some cases it may not be found expedient to employ the same.

The operation of the refrigerating medium need not be continuous as it is apparent that operation for but a short time will be sufficient to lower the temperature of the liquid, to remain as stored refrigeration through a range of 32° to 38° for several hours, after which, the refrigerating system will be automatically set into operation through the action of valve 28.

This modified arrangement has been found to be highly advantageous in localities where water ice is not immediately available or where automatic refrigeration is more desirable.

Manifestly the construction as shown and described is capable of some modification and such modification as may be construed to fall within the scope and meaning of the appended claims is also considered to be within the spirit and intent of the invention.

What is claimed is:

1. Apparatus for the removal of non-condensable gases from a refrigerating system comprising a refrigerant container having a separator therein, said separator comprising a pipe positioned vertically within said container, a core disposed within said pipe, means cooperating with said core and the inner surface of said pipe defining a spiral passage therethrough, means effecting communication between said spiral passage and the receiver of said system whereby the vaporized refrigerating fluid and entrained non-condensable gases from said receiver are subjected to the cold inner surface of said pipe in thin layers to effect condensation of said vaporized refrigerating fluid, an exhaust line for non-condensable gases connected to the upper end of said pipe, and a transparent container having liquid therein, receiving the outlet end of said exhaust line to produce a means for observing the escape of said non-condensable gases from said pipe.

2. Apparatus for the removal of non-condensable gases from a refrigerating system including a receptacle having a cooling medium therein maintained at a constant temperature, a separator comprising a pipe disposed within said receptacle and submerged in said cooling medium,

5 a core in said pipe, means interposed in the space between said core and pipe and cooperating therewith to define a spiral passage within said pipe for subjecting thin layers of vaporized refrigerating fluid and entrained non-condensable gases introduced into said pipe from the receiver of said refrigerating system to said cooling medium, to effect condensation of said refrigerating fluid, means into which said non-condensable gases are exhausted to observe the speed of exhaust thereof, and a common means for conveying gas laden fluid from and returning condensate to said receiver.

3. Apparatus for the removal of non-condensable gases from a refrigerating system, in combination with the receiving tank of said system, a receptacle containing a refrigerant at a constant temperature, a pipe axially disposed in and extending substantially the full length of said receptacle, a core coaxially disposed in said pipe but of a diameter slightly less than the inner diameter of said pipe, means intermediate the walls of said core and pipe, cooperating with each to define a spiral passage substantially the length of the latter and through which vaporized fluid is passed in thin layers to effect condensation, means effecting communication between said pipe and receiving tank and connected to the upper end of said spiral passage and means communicating with means exteriorly of said receptacle for receiving and releasing extracted gases.

4. Apparatus for extracting non-condensable gases from a refrigerating system in combination with the receiver of said system, a receptacle adapted to contain a refrigerant, a pipe disposed centrally in said receptacle in heat exchange relation with said refrigerant, having communication with said receiver at its lower end and provided with a gas release at its upper end, means within said pipe to constrain fluid from said receiver to flow against the wall of said pipe spirally and in a thin stream to effect separation of the gas and fluid and means exteriorly of said receptacle for observing the rate of release of said gases.

5. An extractor for non-condensable gases in a refrigerating system, comprising in combination with the receiver of said system, a hollow, tubular body having one end in fluid exchange communication with said receiver and a gas exhaust at its opposite end, means within said body to constrain vaporized fluid to flow against the inner walls of said body in a thin spiral stream, means for maintaining the exterior of said body at a constant low temperature to effect condensation of said fluid and means communicating with the exhaust of said body for observing the rate of said exhaust.

LOUIS P. REISS.
